UNITED STATES PATENT OFFICE

136,564

DESIGN FOR A BELT

Shizuko S. Oya, Honolulu, Territory of Hawaii

Application July 22, 1943, Serial No. 110,731

Term of patent 14 years

To all whom it may concern:

Be it known that I, Shizuko S. Oya, a citizen of the United States and a resident of the city of Honolulu, Territory of Hawaii, have invented the new, original, and ornamental Design for a Belt, of which the following is a specification, reference being had to the accompanying drawing, forming part thereof, in which:

Fig. 1 is a front view of a portion of a belt embodying my design.

Fig. 2 is a rear view thereof.

Fig. 3 is an edge view thereof.

I claim:

The ornamental design for a belt, substantially as shown.

SHIZUKO S. OYA.
